AIR VENTING VALVE

John Upton, Wayland, Mass., assignor to Anderson Products, Inc., Cambridge, Mass., a corporation of Massachusetts

Application March 5, 1942, Serial No. 433,439

5 Claims. (Cl. 137—122)

This invention relates to hot water heating systems and is particularly concerned with means for eliminating trapped air from radiators or such other places as it may accumulate.

In hot water heating systems, the air must be expelled from the system while it is being filled with water, and air that may be distilled from the water during subsequent operation must also be vented from the radiators from time to time.

Accordingly, the present invention is concerned with a valve which is designed to operate automatically to vent air from the radiators or from other high points where air may be trapped at the time the system is being filled, and to vent any additional air that may thereafter accumulate at the points in question.

Heretofore it has been customary to eliminate air from the radiators through the use of a manually controlled valve. In the present invention it is contemplated that the automatically operating valve shall be connected to the radiator at the location of the previously referred to manually operated valve. In this way, no disturbance of the other equipment is necessary.

The foregoing and other objects of the invention will become more apparent as the description proceeds with the aid of the accompanying drawing, in which,

Fig. 1 is a diagrammatic showing of a hot water heating system of the type with which the valve of the present invention may be used.

Fig. 2 is a vertical cross section of the valve.

Fig. 3 is a top plan view of the valve with cap removed.

Figs. 4, 5 and 6 show successive positions of the various valve parts that prevail during the venting of air through a heating cycle.

Fig. 7 shows means for varying the venting capacity.

In Fig. 1, a typical heating system is shown having a boiler 2, a heat source 4, which may be a thermostatically controlled oil burner of known construction, and mains 6 and 8 leading to risers 10 and 12 respectively, which supply hot water from the boiler to radiators 14 and 16. Return mains 18 and 20 join in a common pipe 22 leading back to the boiler.

A water supply line 24 provides the original or additional water when needed through valve 25.

The system disclosed is a so-called sealed system, but the valve of the present invention will function with any type of system, whether sealed or open. An expansion tank 26, connected as shown, provides for expansion of the water through compression of the air 27 in the upper part of the tank.

The air venting valves that constitute the invention are shown at 28 on radiators 14 and 16. These are ordinarily connected as near the top

of the radiators as possible and may be attached by the use of a suitable fitting.

It will be understood that the system just described is merely illustrative of any hot water heating system in which air is present before the system is filled and in which, while in use, air is gradually distilled from the water to accumulate at the tops of the radiators and other high spots where the flow of water is not sufficient to carry it away.

It will be understood further that the valve of the present invention may be attached any place in a system from which it is desired to vent trapped air. The system with which the valve may be used may be one in which either the water is heated periodically or maintained at a constant temperature. The valve will give satisfactory results with systems that are thermostatically or manually controlled.

In a system of the type described, when heat is supplied, the water expands and there is an increase in pressure throughout the system. That part of the heating cycle during which the water is being heated and expanding will be referred to as the on part of the heating cycle, while the other portion of the cycle, in which the burner or heat source is off or diminished, with the water cooling and contracting, will be referred to as the off part of the cycle.

The general operation of the valve contemplates continuous venting therethrough so long as the pressure of the trapped air is in excess of the pressure at which the valve is set to open. That is to say, during the initial filling of the system, the valve will vent continuously until the trapped air is expelled, and thereafter, during cyclical operation of the system, such air as may accumulate will likewise be vented continuously until the radiator to which the valve is attached is again filled.

By the provision of adjustment means, the valve can be set to vent at a pressure which will conform to the pressure developed both when the system is being filled and during subsequent heating cycles.

Referring to Fig. 2, the valve, generally referred to as 28, comprises a base 30 having a screw threaded nipple 32 at its lower end for attachment to any suitable radiator connection. A bore 33 extends vertically through the nipple and base. The upper end of base 30 is threaded at 34 to receive a locking nut 36 having an upper flange 38 suitable for engaging an out-turned flange 40 on the lower end of a casing 42.

Casing 42 is divided by a horizontal partition 47 into upper and lower chambers 44 and 46, in which are contained the valve mechanisms.

In the lower chamber 46 is a supporting insert 48 set in a suitable cavity in base 30. This insert has a series of holes 50 therethrough which per-

mit the passage of air from bore 33 to the lower chamber 46. A screen 52 is held in place by insert 48 to insure against the passage of any large-size particles from the radiator to the valve which might affect the operation of the latter.

Insert 48 carries a vertical support 54 on which is positioned a diving bell type float 56 having a centrally located pin 58 that normally engages with the upper end of support 54, as shown in Fig. 4. Supporting the pin 58, on the upper side of the float, is a valve member 60 undercut at 62 to provide a circular bearing surface against a rubber valve disk 64 set in a recess in the underside of partition 47. An aperture 66, aligned with disk 64, extends through partition 47, and the upper end of pin 58 extends part way therethrough, thus acting as a guide for valve member 60. There is, however, ample clearance between pin 58 and aperture 66 so as not to impede the flow of air therethrough.

Surrounding the upper end of aperture 66 is a valve seat 68 against which normally rests a valve disk 70, carried by a supporting member 72 and urged downwardly by a spring 74. The spring is held in position by an externally threaded disk 76 in vertically adjustable engagement with the interiorly threaded opening 78 extending through the top of the casing 42. The upper end of the opening 78 is closed by a cap 80. It will be noted that both disk 76 and cap 80 have passages 82 and 84 therethrough to permit the escape of air from the upper chamber to the atmosphere.

By adjustment of disk 76, the pressure exerted by spring 74 on the upper valve 70 may be varied. The setting of the upper valve is determined by the pressures that are normally developed in the system during filling and during the on cycle.

In Figs. 4, 5 and 6 are shown the positions the various valve parts take during a heating cycle. In Fig. 4, the parts are shown in the position they assume during the major portion of the off cycle and during the early portion of the on cycle. The upper valve is still unopened because the casing pressure is below that necessary for venting.

In Fig. 5 is shown the position the parts momentarily assume immediately following the substantially complete venting of air, with the lower valve closed by rising water in the lower chamber, or by rapid air flow through aperture 66.

In Fig. 6 the parts have assumed the position that will prevail immediately following the conditions shown in Fig. 5 and during the latter part of the on cycle and the commencement of the off cycle. The upper valve has closed because of the elimination of the lower casing pressure through the closing of valve 60.

The operation of the valve parts in detail is as follows. Considering first the operation of the valve during the initial filling of the heating system, water valve 26, controlling the water supply, is opened, thereby admitting water to the system. As water fills the boiler and rises through the mains, the pressure of the air above will correspondingly increase. When the pressure becomes great enough, valve 70 will be forced upwardly from its seat and air will thereupon vent continuously through aperture 66 and the ports 82 and 84 to the atmosphere. The lower valve 60 will remain open during this period, as the velocity of the escaping gas will not ordinarily be sufficient to drive the float and associated parts upwardly to close the lower valve. When the system and the radiators are full, water will

enter the lower valve chamber 46, causing float 56 to rise, thereby closing the lower valve and stopping further escape of air. With the pressure removed, the upper valve will thereupon reset itself.

As the operation of the system continues thereafter, additional air will be distilled from the water and will collect in the top of the radiators. The water level will gradually drop, and as a result float 56 will descend with the receding water, thereby opening lower valve 60.

This additional accumulated air is thereafter vented during one or more of the subsequent heating cycles. The action of the valve for the automatic venting of this secondary accumulation of air is as follows. During the off part of the heating cycle, pin 58 will rest on support 54, with the lower valve open and the upper valve closed. Upon the development of heat in the water and corresponding expansion, the trapped air will be compressed, bringing increasing pressure to bear on the under side of valve disk 70. As this pressure becomes greater, it will finally exceed the downward force exerted by spring 74 so that the upper valve will open and the compressed air will be vented through aperture 66 and the upper ports 82 and 84 to the atmosphere. As the air is vented, the pressure within the valve will decrease. If the pressure decreases below that at which valve 70 closes, the latter valve may then close before all of the air has been vented. If, however, the pressure of the trapped air is maintained, the water level in the radiators will rise until chamber 46 again receives water, thereby lifting float 56 to cause the lower valve to close, thereby cutting off further escape of air.

Immediately upon the closing of aperture 66 by the lower valve, the upward pressure against the upper valve 70 will be dissipated so that the upper valve will reseat itself, as shown in Fig. 6, thereby providing a double seal for aperture 66.

Thereafter the lower valve will remain closed until the water level has dropped and the pressure within the lower area 46 decreases to an amount only slightly greater than the pressure which is required to open the upper valve. That is to say, if the pressure necessary to open the upper valve is, for example, 15 lbs. per square inch, the lower valve 60 will not fall away from the position shown in Fig. 6 to resume its normal position as shown in Fig. 4 until the pressure in lower chamber 46 has dropped to approximately 15½ lbs. This, of course, will not occur until the heat source has been discontinued and the water is cooling and contracting, with a corresponding reduction of pressure of the trapped air. A one-half pound per square inch pressure in excess of the setting of valve 70 will maintain lower valve 60 closed. This differential will vary, however, according to the details of the construction.

As the water and pressure drop, the valve parts reassume the positions shown in Fig. 4, in which condition they are ready for a repetition of the cycle just described.

In order to provide ready adjustment of the spring 74, it is convenient to place suitable markings on the top of disk 76, as shown in Fig. 3. With the cap 80 removed, disk 76 may be turned by the insertion of a screw driver in slot 86 until the number indicating the desired pressure is alongside a reference point 88 located in the upper surface of the threaded neck. Since most hot water systems are equipped with a pressure

gauge, the pressure that will be reached on each heating cycle may be readily determined and the valve adjusted accordingly.

The valve as thus far described will operate under practically all conditions that are to be found in connection with hot water heating systems. Occasionally, however, the pressure of the air being vented during filling of the system may become so great that air will escape through aperture 66 at a sufficiently high velocity to drive valve member 60 and the associated parts to closed position as shown in Fig. 5. It would be undesirable for the valve to close during filling of the system before all of the air has been vented. Accordingly, if the valve is to be used in systems where very high pressures are developed with accompanying high velocities through aperture 66, it will be appreciated that any tendency of the gas flow to close the lower valve prematurely may be overcome by reducing the effective area of aperture 66 to a point where the necessary throttling action is provided.

The variation of the effective area of aperture 66 might be accomplished by the introduction of a perforated disk into the upper part of aperture 66. Such a disk is shown in Fig. 7 at 90 with apertures 92 therethrough. By having a sufficient supply of disks of varying capacity, the flow may be controlled as needed.

I claim:

1. A valve of the type described, comprising a casing having an entrance port and an exit port, a partition dividing said casing into upper and lower chambers, an aperture through said partition having valve seats at its lower and upper ends, a support in said lower chamber, a float carried by said support, a first valve member carried by said float in such position that the lower end of said aperture is normally open, said float adapted to rise and close the lower end of said aperture when the water rises in said lower chamber to a predetermined level, and a loaded second valve member normally resting on said upper valve seat to close the upper end of said aperture against pressures less than a predetermined degree, the effective area of said first valve member against which the pressure in said lower chamber may act being such that after said first valve member has been closed by rising liquid it will remain closed after the water has receded until the pressure in the lower chamber has also decreased to a pressure which is but slightly in excess of the pressure required to open said second valve member.

2. A valve for venting air from a hot water heating system comprising a casing, a fixed aperture through the upper part of said casing and provided with valve seats at its ends, a first valve member of effective area substantially greater than said aperture and limited in its downward movement and capable of upward movement to engage the lower valve seat, a second valve member also having an effective area substantially greater than said aperture and normally in engagement with said upper valve seat but movable therefrom under the influence of pressure in said aperture in excess of a predetermined degree, a float connected to said lower valve member whereby the latter may be maintained in position to close the lower end of said aperture under the influence of water in said casing above a predetermined level, the weight of said first valve member and float in relation to the effective area of said first valve member being such that pressure in said casing only slightly greater than the pres-

sure required to move said second valve member from its seat will hold said first valve closed in the absence of water in said casing after being first closed by rising water.

5. A valve for venting air from a hot water heating system, comprising a casing, an aperture through the upper part of said casing, outer and inner valve seats at the ends of said aperture and of substantially greater area than said aperture, an outer valve member normally in engagement with said outer valve seat and operable to open under the influence of pressure in said casing in excess of a predetermined degree, an inner valve member adapted to engage said inner valve seat and supported in such position that the inner end of said aperture will be normally open, a float connected to said inner valve member capable of raising the latter to close the aperture upon the entrance of water into said casing above a predetermined level, the construction of said inner valve member and float being such that when the pressure in said casing is sufficient to open said outer valve to vent air, said inner valve will remain open, but when said inner valve has been closed by the presence of water in said casing, said inner valve will be maintained closed after the water in said casing has receded to a level below that at which said inner valve was closed by casing pressures only slightly in excess of the pressure required to open said outer valve.
10. 4. A valve for venting air from a hot water heating system, comprising a casing having inlet and outlet ports, said outlet port formed by an aperture through a fixed portion of said casing, spring pressed means for maintaining said aperture normally closed while the pressure within said casing is below a predetermined degree, other means for maintaining said aperture closed while water is in said casing above a predetermined level, said spring pressed means movable to open said aperture when the pressure in said casing has increased beyond said predetermined degree and while the water in said casing is below said predetermined level, and said spring-pressed means and said other means being constructed and arranged to maintain said aperture closed after it has been initially closed by water rising above said predetermined level and after the water has receded below said level, under the influence of pressure in said casing at least slightly greater than the pressure required to cause normal venting.
15. 5. A valve of the type described comprising a casing having an inlet port and an outlet port, a partition dividing the casing into upper and lower chambers, an aperture through said partition, lower valve means for closing the lower end of said aperture under the influence of rising liquid in said lower chamber, and upper valve means normally maintaining the upper end of said aperture closed and operable to open when the pressure in the lower chamber exceeds a predetermined degree and said lower valve means is open, the weight of said lower valve means being so related to the effective seating area of said lower valve means that a pressure in said lower chamber slightly in excess of the pressure required to open said upper valve means will be sufficient to maintain said lower valve means closed following closure by rising liquid level and after the liquid has receded below the level reached in performing the initial closing operation of said lower valve means.

JOHN UPTON.
